UNITED STATES PATENT OFFICE.

FERDINAND SCHRÖDER, OF BERLIN, GERMANY, ASSIGNOR TO INTERNATIONALE SIEGWARTBALKEN-GESELLSCHAFT, OF LUZERN, SWITZERLAND.

MANUFACTURE OF CONCRETE ARTICLES.

Application filed July 22, 1920. Serial No. 398,299.

(GRANTED UNDER THE PROVISIONS OF THE ACT OF MARCH 3, 1921, 41 STAT. L. 1313.)

To all whom it may concern:

Be it known that I, FERDINAND SCHRÖDER, merchant, a citizen of the German Republic, and residing at Berlin, Germany, have invented certain new and useful Improvements in the Manufacture of Concrete Articles (for which I have filed applications for patents in the following countries: Germany March 29, 1919, Austria November 5, 1919, Hungary November 21, 1919, Poland January 2, 1920, Czecho-Slovakia December 15, 1919, Great Britain December 6, 1919, France December 1, 1919, Italy November 12, 1919, and Finland December 8, 1919), of which the following is a specification.

This invention relates to a method of making articles of pebble or gravel concrete, having inserted patches or places formed of asbestos cement concrete, which is capable of being worked.

Concrete is now largely used for the making of many articles which were formerly made of wood, such for instance, as railway sleepers, beams, columns or uprights, masts and the like. As pebble concrete, after hardening and setting or binding, is not capable of being worked, it is necessary to form those parts of the pebble concrete articles, which, as in the case for instance, of railway sleepers are intended to afterwards receive screw bolts, nails or the like for the purpose of fastening the rails, of material adapted to be operated on, and for this purpose asbestos cement concrete is preferably selected by reason of its capacity of being easily worked upon and its imperishable qualities, and also because it combines thoroughly with the pebble concrete without the formation of intervals, crevices, cracks or the like at the joints.

In the accompanying drawing:—

Fig. 1 is a sectional view of a body of gravel and cement provided with an insertion of asbestos cement, in accordance with my invention.

Fig. 2 is a plan of the same.

In the drawing, the body of gravel and cement is indicated at *a*, the insertion of asbestos cement is indicated at *b*, and the woven wire is indicated at *c*.

In order that in the mutual binding or setting of the different kinds of concrete, these should not become mingled with one an-

other, and gravel particles from the gravel or pebble concrete should not pass over into the adjacent asbestos cement concrete, which would deleteriously affect the capability of the latter to be worked upon, in filling in the two different kinds of concrete into the mould, sheet metal shields or sliding pieces have hitherto been employed for separating them, which shields were withdrawn when the mixtures had been completely introduced and smoothed. If this withdrawal occurs too soon, the penetration of particles of gravel or pebbles into the asbestos cement concrete cannot be prevented. If the slides or shields are withdrawn too late, the homogeneous connection of the different mixtures when setting is affected, and later on crevices or cracks are easily formed, or the inserted asbestos concrete portions gradually become entirely loosened. Further, the slides can only be employed where it was a question of straight or only simple curved bordering surfaces or faces.

Now by this invention, sieves or cloths of thin wire, sheet metal, asbestos yarn, or other suitable material may be employed for obtaining a certain separation between the two different kinds of concrete during the simultaneous ramming in, which is effected by hand or mechanically, or in the common filling or shaking in of the two different kinds of concrete, and these dividing substances remain in the article to be made, even after its completion, but have such a width of mesh, that while they prevent the passage of pebbles, or gravel particles from the gravel or pebble concrete into the asbestos cement concrete with certainty they do not impede the common homogeneous binding together of the two different kinds of concrete at the contact faces or places.

As the sieves or cloths remain in the article even when finished, and therefore do not need to be withdrawn before the setting, they may be of any suitable form and hence the formation of the asbestos cement concrete parts which are to be embedded in the pebble concrete is not restricted to the narrow limits which naturally result where slides or shields are employed, which have to be withdrawn before the setting of the concrete.

According to the process forming the object of the present invention, there are thus

obtained, articles of pebble concrete having inserted places of asbestos cement concrete, in which both kinds of concrete are combined fully homogeneously, to a monolithic unity, and in which the asbestos cement concrete places can be operated on in any suitable way. They may be planed, cut, bored, and nails and screws can also be driven into them, so that other constructional parts may 10 be thereby connected with them securely and permanently.

Having now described my invention, what I desire to secure by a patent of the United States is:—

15 1. The method of making concrete articles composed of more than one character of concrete, which consists in embedding a screen in the article, during the simultaneous ramming in, at the bounding line between the 20 various kinds of concrete, to prevent the

kinds of concrete from mixing, and leaving said screen permanently in the article.

2. The method of making concrete articles composed of more than one character of concrete, one having particles larger than those of another, which consists in embedding in the article, at the bounding line between the various kinds of concrete, a screen having meshes of such size as to permit the smaller particles of the various kinds of concrete to mix and prevent the larger particles of one kind of cement to mix with the particles of another, and leaving said screen permanently in the article.

In testimony whereof I have affixed my signature in presence of two witnesses.

FERDINAND SCHRÖDER.
